COKE OVEN BATTERY

Charles V. McIntire, Short Hills, N. J., assignor
to Semet-Solvay Engineering Corporation,
New York, N. Y., a corporation of New York

Application February 9, 1934, Serial No. 710,445

6 Claims. (Cl. 202—151)

This invention relates to coke ovens, and more particularly, to so-called vertically flued combination by-product coke ovens arranged to burn in the vertical flues flanking the coking chambers either lean gas, such as producer or blast furnace gas, which for efficient operation requires preheating, or rich gas, such as coke oven gas, which requires no preheating.

One object of this invention is to provide a by-product coke oven designed to accurately control the quantity of air fed to the regenerators communicating with the combustion flues, as well as the percentage of inert diluent gas introduced into the combustion flues to effect the combustion of a rich gas, such as coke oven gas, in long flames throughout the flues resulting in uniform heating of the heating walls.

Another object of this invention is to provide a procedure for introducing air under pressure into the inflow regenerators of a coke oven battery and employing the suction created by the introduction of the air through aspirators to effect the flow of products of combustion into the regenerators and thence into the combustion flues.

Other objects and advantages will appear from the following detailed description.

It has been proposed to supply a neutral gaseous diluent to the flues of a coke oven battery for the purpose of lengthening the flame so as to equalize temperature conditions throughout a maximum area of the heating wall and prevent intense heat concentration in localized portions of the walls. The well known Semet-Solvay zig-zag horizontally flued coke oven, in which gases burn with almost uniform intensity throughout a series of horizontal flues, each of which is approximately forty feet long, involves such operation, uniform heating being obtained because of the presence of a large excess of products of combustion in the gas stream flowing through the flues. Patent Nos. 1,176,066 and 1,176,067, of March 21, 1916, to H. Koppers, disclose such operation in connection with a vertically flued coke oven battery. In the oven of the Koppers patents, it will be noted that the mixture of air and products of combustion from the chimney flues flow into the regenerators through the same wind boxes as the products of combustion from the regenerators flow into the chimney flues. Furthermore, the flow of the mixture of air and products of combustion into the regenerators is effected by the control of the same dampers or valves which regulate the reverse flow of products of combustion from the regen-

erators into the chimney flue. These valves set for flow in one direction, e. g., flow of products of combustion from the regenerators into the chimney flues, would not be in proper position for controlling the flow in the opposite direction, e. g., flow of the mixture of air and products of combustion from the supply flue into the regenerators. Hence, with the construction of the Koppers patents, it was not possible to obtain effective control of the volume of air and diluent gas introduced into and through the regenerators into the combustion flues.

In accordance with this invention, the air is introduced under pressure which may be of the order of three inches water gauge and is metered through a regulating valve or orifice individual to each regenerator before being mixed with products of combustion so that each regenerator can be supplied with its exact requirements of air. The air flows to each regenerator through an aspirator which effects the flow of products of combustion to the regenerator. By adjusting the aspirator mechanism, each of which is individual to an inflow regenerator, a desired controlled volume of products of combustion can be fed to the regenerator. Hence, this invention permits the accurate control of the quantity of air, as well as the percentage of diluent neutral gas introduced into each regenerator.

In the accompanying drawings, forming a part of this specification and showing for purposes of exemplification a preferred form of this invention without limiting the claimed invention to such illustrative instance—

Fig. 1 is a crosswise vertical section through a coke oven battery embodying the improvement of the present invention, the view being taken longitudinally through a heating wall and regenerators and in a plane indicated by the line 1—1 of Fig. 2;

Fig. 2 is a fragmentary vertical section through a coke oven battery taken longitudinally of the battery in a plane passing through the charging openings leading into the coking chamber and taken on line 2—2 of Fig. 1; and

Fig. 3 is a horizontal section through a coke oven battery taken longitudinally of the battery in a plane indicated by the line 3—3 of Fig. 2.

In the preferred embodiment illustrated on the drawings, the invention is shown incorporated in a combination coke oven battery and the present description will be confined to the present illustrated embodiment of the invention in such oven battery. It will be noted, however,

that the novel features and improvements are susceptible to other applications, such for example as vertically flued coke ovens in which the flues are not arranged in four groups, as in the case of the oven shown on the drawings. Hence, the scope of this invention is not confined to the embodiment herein described.

In the drawings, referring to Figs. 1 and 2, there is shown a combination by-product coke oven embodying in its construction a plurality of heating walls 12 and a plurality of intermediate crosswise extending horizontally elongated coking chambers 13. The heating walls form the side walls of the respective coking chambers, the heating walls and the coking chambers, together with the superstructure of the oven battery, being supported by massive supporting walls 14 positioned directly beneath the heating walls 12. The supporting walls 14 rest on and are supported by a flat mat or platform which constitutes the sub-foundation for the oven battery.

The coal or other material to be coked is charged into the coking chambers 13 through charging holes 15 located in the top 16 of the oven battery and positioned directly above and communicating with the coking chambers 13. The charging holes are equipped with the usual removable covers which are removed during charging of the individual coking chambers and are placed in position to close the tops of said coking chambers during the entire coking operation. The gases evolved in the coking chambers pass from the ducts thereof through the usual ascension pipes (not shown) into the usual gas collector main system which communicates with the by-product recovery apparatus.

Referring more particularly to Fig. 1, it will be noted that each heating wall 12 is composed of a plurality of vertical combustion flues formed by transverse flue walls 17. The flues of each heating wall are operatively disposed in four groups of consecutive flues, the groups being numbered for convenience 1, 2, 3, and 4, each group of flues being constituted of a like number of flues, six in the embodiment shown on the drawings, and the flues of each group operating concurrently for flow in the same direction. During one cycle of operation, indicated by the arrows on Fig. 1, the flues of groups 1 and 3 operate concurrently as inflow flues, while similarly the flues of groups 2 and 4 operate concurrently as outflow flues. The tops of flue group 1 are communicably connected with the tops of flue groups 2 by a horizontal passage or bus flue 18 while the flues of groups 3 and 4 are interconnected by the horizontal bus flue 19. Bus flues 18 and 19 of each heating wall are placed in longitudinal alignment at a level somewhat below the usual level of the charge in the coking chambers. The flow through each flue may be regulated by a slide brick or damper brick 21 movable on ledge 22 (Fig. 2) on the sides of the flues to vary the extent of the passage 23 connecting the vertical flues with the horizontal bus flues. Slide or damper bricks 24 are also provided at the base of the flues for regulating the flow from the regenerators, hereinafter described, to the flues. Each slide brick 21 or 24 may be advanced more or less over the passage 23 or ducts communicating with the regenerators, respectively, through access flues 25 which extend from the tops of the vertical flues. Access flues 25 also afford access to the gas nozzles herein-after described located in the bottoms of the flues.

The regenerators of the battery are located be-

neath the coking chambers 13 and extend crosswise of the battery parallel to the coking chambers 13 between the supporting walls 14. In the middle lengthwise vertical plane of the battery, a vertical partition 27 is positioned, running the full length of the battery and extending all the way from the top of conduit 53, hereinafter more fully described, to the top of the battery. This partition divides the regenerators and connected groups of flues into two sets of inflow and outflow regenerators and flues, the respective sets being located on opposite sides of the battery, thereby permitting control from opposite sides of the battery of the flow of air and gas into and through the regenerators and connected flues.

The regenerators are arranged lengthwise of the battery in series of two regenerators 28, 29 connected to the flues of each heating wall, each regenerator being connected to corresponding groups in the heating walls on opposite sides of the coking chamber above. Partition wall 31 (Fig. 1) divides the regenerator sections at the pusher side of the battery with respect to the aforementioned partition wall 27 into two sections, numbered for convenience 1 and 2 (Fig. 1), regenerator section 1 being connected to group 1 of the flues and regenerator section 2 being connected to group 2 of the flues in the pair of heating walls defining the coking chamber above. Likewise, partition wall 32 divides the regenerator sections at the coke side of the battery into two sections, 3 and 4, section 3 being connected to group 3 and section 4 to group 4 of the flues in the pair of heating walls defining the coking chamber above. All the regenerator sections 1 and 3 during one cycle of operation of the battery operate for inflow into groups 1 and 3 of the flues, respectively, the products of combustion passing down through groups 2 and 4 into regenerator sections 2 and 4, respectively, which operate for outflow. Thus, crosswise of the battery, the regenerator sections alternate as inflow and outflow regenerator sections and longitudinally of the battery the regenerator sections in longitudinal alignment are all in the same phase.

When operating with an extraneously derived gas as the fuel burned in the flues, regenerators 29 preheat producer or other extraneously derived gas and the regenerators 28 preheat the air necessary for combustion of the gas in the flues. When operating with fuel gas fed directly to the flues through the gas channels 33, 33', 34, 34', hereinafter more fully described, both regenerators 28, 29 connected to the flues of each heating wall are preferably used to preheat air admixed with a neutral gaseous diluent, such as waste gas, fed to the flues.

Each section of the regenerators 28, 29 is connected with its group of flues through a horizontal sole flue or passage 35 which, as shown in Fig. 2, may be substantially triangular in section. The base of passage 35 communicates with the regenerator section below through a plurality of spaced ports or points 36, preferably one port for each flue connected to the sole passage 35. From the sides of the sole flue 35 lead upwardly extending ducts 37, one individual to each flue, the ducts leading into the bases of the flues, the ducts from the regenerators 28 joining the ducts from regenerators 29 immediately below the flue, as shown in Fig. 2, and both ducts join to form a single duct or passage which leads into the base of the flue. Hence, admixture of gas and air from regenerators 29 and 28, respectively, takes place im-

mediately below the flues before these media enter the flues and the mixture burns upwardly in a vertical direction, the flow being under control of the damper or slide bricks 24 in the base 5 of each flue. This arrangement of regenerators and flues results in uniform distribution of the gas to the individual flues, efficient admixture and burning of the gas and air in the flue, with consequent uniform temperatures in the heating 10 walls and coking chambers, and also a longer life for the brickwork in the flues since the direction of flow of the gas and air at the points of entry into the flues is directly upward and the side walls of the flues at the points of entry of 15 gas and air are not in the direct path of flow of the burning gases.

It will be noted that sections 1 and 3 of regenerators 28 and 29 feed air and gas, respectively, to the inflow flue groups 1 and 3, respectively, the products of combustion passing through the horizontal bus flues 18, 19 through outflow flue groups 2 and 4, respectively, into and through regenerator sections 2 and 4, respectively. Thus, during one cycle of operation 25 lengthwise of the battery, sections 1 and 3 of regenerators 28 and 29 are inflow air and gas regenerators, respectively, and regenerator sections 2 and 4 are outflow waste gas regenerators, respectively. Upon reversal, the regenerators 30 and connected flues operating for inflow become outflow regenerators and flues, and those operating for outflow become inflow regenerators and flues. Reversal of flow in the regenerators takes place crosswise of the battery between sections 35 1 and 2 on the one hand and sections 3 and 4 on the other hand, so that during one cycle, regenerator sections 1 and 3 operate for inflow and 2 and 4 for outflow, and upon the next cycle, sections 2 and 4 operate for inflow and 1 and 3 for 40 outflow. The regenerator sections are thus heated in alternation by the hot combustion products that pass out from the combustion flues and then impart such heat to the medium fed therethrough into the combustion flues.

Each regenerator is a chamber containing 45 brickwork commonly called "checkerbrick". In the base of each regenerator is built up a short partition wall integral with supporting walls 14 as shown in Fig. 2. The partition wall 39, in 50 effect, provides passages substantially rectangular in cross-section disposed in the base of the regenerators 28 and 29, openings being formed in the partition walls 31, 27, and 32 where the passages extend therethrough.

The structure of the passages in the base of 55 the regenerators and the connections between these passages and chimney flues 41 and 42 located on the pusher and coke sides of the battery, respectively, are best shown in Figs. 1 and 3 and 60 since this structure is identical for all regenerator pairs 28, 29, it will be described in detail in connection with only one such pair. Viewing the pair of regenerators at the base of Fig. 3, it will be noted that passage 43 is provided in the 65 base of section 1, regenerator 28, the top of this passage being in open communication with the regenerator section, end 44 thereof terminating at the partition wall 31 and the other end being in communication with manifold 45 (Fig. 1). 70 Manifold 45 is provided with an air valve 46 for each regenerator, controlling the flow of air into the passages 43, a waste stack valve 47 for placing passages 43 into communication with the chimney flue 41, and a gas valve 48, shown in 75 dotted lines, for each regenerator 28 to permit

flow of gas from gas main 51 into the gas regenerator 29. The valve structures, since 5 per se they form no part of the present invention, are shown diagrammatically on the drawings. It will be understood that the valves for all the 10 regenerators are interconnected and operated from a common source, upon reversal valves 47 being fully opened, as shown to the right of Fig. 1, while valves 46 and 48 are simultaneously closed. The structure of the valves and manifold associated with chimney flue 42 is identical 15 with that hereinabove described.

Operating with lean gas burned in the flues, air flows through the valve port controlled by valve 46, into passage 43, and thence to section 1 20 of regenerators 28. Lean gas flows from the main 51 into a conduit or passage 52 in the base of section 1 of each gas regenerator 29. One end of passage 52 is defined by the partition 25 wall 31, i. e., terminates at this partition wall; 30 the other end communicates with the manifold 45; and the top is in open communication with the regenerator section 1. The gas and air, as hereinabove described, pass through regenerator section 1, up through group 1 of the flues; the 35 products of combustion pass down through group 2 of the flues into regenerator sections 2 of regenerators 28, 29. Regenerator section 2 of regenerator 28 has a conduit or passage 53 in line with conduit 43 of section 1. One end of 40 conduit 53 is closed by partition 31, i. e., terminates at partition 31, as shown in Fig. 1. The top is in open communication with the regenerator section 2 and the passage extends through walls 27 and 32 into communication with the 45 manifold 45 on the coke side of the battery. In regenerator section 2 of the gas regenerator 29, conduit 54 leads from the base of the regenerator, through partition walls 27, 32, into manifold 50 45 on the coke side of the battery.

A passage or conduit 55 extends from the manifold 45 on the pusher side of the battery through the side wall of the battery and the partition walls 31 and 27 into communication with section 3 of regenerator 28. The top of passage 55 within regenerator section 3 is open so that this conduit 55 is in communication with this regenerator section. Conduit 55 ends at the wall 32. The 55 fourth regenerator section is provided with a short conduit 56 open at its top and leading into manifold 45 at the coke side of the battery. Similarly, regenerator sections 3 of regenerators 29 are provided with passages 57 leading from the manifold on the pusher side of the battery through walls 31, 27, terminating at wall 32 and 60 in open communication through its top with sections 3 of regenerators 29. A short conduit 58, similar to conduit 56, places section 4 of regenerators 29 into communication with the manifold on the coke side of the battery.

The flow through the conduits or passages and connected regenerators is indicated diagrammatically on Fig. 3. The letters A and G placed in the conduits indicate the flow of air and gas, respectively, in the conduit in which they are positioned. The letters A' and G' indicate flow of air and gas, respectively, in the regenerator section in which they are positioned. The arrows in full lines indicate flow into a conduit and connected regenerator. The arrows in dotted lines indicate flow of products of combustion out of regenerators through conduits into the chimney flue in communication therewith.

Thus, referring to Fig. 3, the full line arrow and letter A in conduit 43 indicate a flow of air 75

from the atmospheric into this conduit. The letter A' in regenerator section 1 indicates flow of air from conduit 43 into this section. The full line arrow and letter G in conduit 52 indicate flow of gas from the gas main 51 into this conduit, and the letter G' in regenerator section 1 of regenerator 29 indicates flow of gas in this regenerator section. As above described, the gas and air flow into group 1 of the heating flues above regenerator section 1, the resultant products of combustion flowing down through group 2 into regenerator sections 2, as indicated by the letters P'C'. The dotted line arrows in conduit 53 and letters PC in this conduit indicate flow of products of combustion therethrough into the chimney flue at the coke side of the battery. Likewise, the dotted line arrows in conduit 54 and letters PC indicate flow of products of combustion therethrough to the chimney flue at the coke side of the battery. Full line arrows and letters A and G in conduits 55 and 57, respectively, indicate flow of air and gas, respectively, into regenerator sections 3 of regenerators 28 and 29. Dotted line arrows and letters PC in short conduits 56 and 58, respectively, indicate flow of products of combustion from regenerator sections 4 into the chimney flue on the coke side of the battery. Upon reversal, the conduits serving for inflow become outflow conduits and flow occurs in the short conduits 56, 58 into regenerator sections 4 and in the longer conduits 53, 54 into regenerator sections 2, the products of combustion passing out of relatively long conduits 55, 57 and short conduits 43, 52, respectively, into the chimney flue at the pusher side of the battery.

Thus, it will be noted that flow in both conduits in sections 1 and 4 is in the same direction, and since pressure conditions are the same in both conduits, no leakage takes place in these sections. Hence, leakage losses in the operation of the battery are minimized. This arrangement has the advantage that not more than two channels extend in each regenerator section and that of the four channels leading from the four sections, no channel is equal to the width of the battery, i. e., the distance regenerator section 1 is positioned from the coke side of the battery; hence, reducing the amount of brickwork required in the construction of the oven battery. Furthermore, by this arrangement of the channels, regenerators and communicating flues, a positive fixed path of flow through the regenerators 1, 2 and the communicating flues and channels, on the one hand, and the regenerators 3, 4 and communicating flues and channels, on the other, is provided; that is to say, air introduced through channel 43 flows through regenerator 1, mixes with the gas introduced into group 1 of the flues, combustion of the gas in group 1 of the flues being supported by this air and the resultant products of combustion passing through group 2 of the flues, down through regenerator 2, out through channel 53 into the chimney flue 42. Upon reversal, air flows through channel 53, up through regenerator 2, supporting combustion of the gas introduced into group 2 of the flues, the resultant products of combustion flowing down through group 1 of the flues, out through regenerator 1, channel 43, into chimney flue 41. In like manner, the flow of gas through the gas regenerators 1 and 2 and the flow of air and gas through the regenerators 3 and 4 occurs along a positive fixed path.

As above indicated, extending crosswise of the battery in the heating walls beneath the base of

the heating flues are two series of gas supply channels 33, 34, and 33', 34'. The pair of conduits on the pusher side of the battery are connected through valve-controlled connection pipes 61 with gas main 62, while the pair of channels 33 on the coke side are connected through valve-controlled pipes 63 with the gas main 64. The channels 33, 34 and 33', 34' are for the purpose of supplying coke oven gas to the inflow flues, channels 33 and 34' supplying groups 1 and 3 of 10 flues and channels 34, 33' supplying groups 2 and 4 when these groups operate for inflow. For this purpose channels 33, 33', 34 and 34' communicate with the flues in the heating walls by ducts 65 (Fig. 2), leading from the channels 15 individual to the base of each flue. Within the ducts 65 are disposed the usual gas nozzles. By means of the valve pipes 61 and 63, gas is supplied to the inflow operating ducts 65, it being understood that the gas supply is concurrently 20 maintained in channels 33 and 34', and shut off from the channels 34 and 33', the supply being reversed with respect to channels 33, 34' and 34, 33' at each reversal.

The channels 33, 33', 34 and 34' are provided 25 with decarbonizing valves 71. These valves may be of any well known design and for purposes of illustration one type of valve is shown which comprises a housing 72 on which is mounted a valve plate 73 controlling the flow of air from the 30 atmosphere into the channels. Movement of plate 73 may be effected by lever 74 pivoted to the housing 72 at 75 and connected to the plate 73. To one end of lever 74 is secured a chain 76 which passes over the sheave 77. It will be understood, of course, that a decarbonizing valve is provided for each channel 33, 33', 34 and 34' and that through the chains 76, the decarbonizing 40 valves are automatically and concurrently operated to permit flow of air through the burner as nozzles into the outflow groups of flues 2 or 3 as the case may be to decarbonize the burners in such flues and to prevent flow of air into the inflow flues of these two groups. The chains 76 are interconnected with the reversal mechanism 45 and are automatically operated thereby.

In the embodiment of the invention shown on the drawings, the exterior chimney flues 41 and 42 extend beneath the regenerators longitudinally from the front to the rear of the coke oven 50 where they empty into a transverse flue 88 (see Figs. 2 and 3) which in turn empties into flue 87 leading into the chimney 88. Auxiliary flues 84 and 85 extend in parallel relation to the flues 41 and 42 and are in communication with the latter 55 flues by means of channels 81, 82 and 83 (see Fig. 1). Flues 84 and 85, like flues 41 and 42, also empty into the transverse flue 88 which discharges into the chimney 88. The dotted lead lines from reference numerals 41, 42, 84 and 85 60 shown in Fig. 3 indicate the position of the several flues with respect to the coke oven and with respect to the flue 86. A damper 89 controls the draught exerted by the chimney 88 on the flues 41, 42, 84 and 85, the pressure in which is some- 65 what below atmospheric.

Air mains 91, 92 are disposed at the opposite sides of the battery and lead into a common main 93 (Fig. 3) which is supplied with air by means of a motor-operated blower or fan 94 which may 70 be of any well-known type. Valves 95, 96 disposed in the branches of the main 93 extending from the fan 94 control the volume of air delivered by the blower to the mains 91, 92. Each main 91, 92 communicates with a series of aspi- 75

rators and since the arrangement and construction of the mains with communicating aspirators at both sides of the battery shown on the drawings are the same, the construction and arrangement of those on only one side of the battery will be described hereinafter. Each manifold 45, there being one such manifold for each channel 43, 52, 53, 54, 55, 56, 57, and 58 of each pair of regenerators, has extending therethrough an aspirator 98. The aspirator comprises a nozzle 99 communicating through pipe 101 with the air main 91 or 92 as the case may be. The discharge outlet of nozzle 99 extends into a conical housing 101, a clearance space 102 being provided between the housing 101 and the nozzle 99. The discharge nozzle 99 and the housing 101 for the regenerator section 2 shown on Fig. 1 are disposed above the passageway 103 connecting the passage 53 with the chimney flue 42. In like manner, the aspirators for the regenerators communicating with the chimney flue 42 are disposed in the passages connecting these regenerators with this chimney flue and the aspirators for the regenerators communicating with the chimney flue 41 are disposed in the passages connecting these regenerators with the chimney flue 41.

Controlling the flow from each air main to the aspirators communicating therewith is a valve 104 having a valve stem 105. All the valve stems on one side of the battery are interconnected and are arranged to be concurrently moved from a position shown at the left of Fig. 1, permitting flow of air to the aspirator nozzles 99 to a position (shown at the right hand side of Fig. 1), interrupting the flow of air from the air main to the aspirator nozzles 99. A butterfly valve 106, each individual to an aspirator nozzle, is disposed in the line connecting the aspirator nozzle with the air main and may be adjusted to give a desired controlled volume of air flow from the main to the aspirator. The butterfly valves 106 once adjusted for any desired flow are not changed during a subsequent operation unless it is desired to change the volume of air introduced into the regenerators.

In operation, the butterfly valves 106 are adjusted to give the desired volume of air flow to the aspirators. The air under pressure, which may be less than one pound per square inch and preferably is of the order of three inches of water, expands through the aspirator, the suction thus created causing flow of products of combustion from the chimney flue 41 or 42 as the case may be, which are at a pressure somewhat below atmospheric. It will be understood that any adjustment in the volume of air fed to the aspirators by the butterfly valve also affects the volume of products of combustion withdrawn through the conical housing of the aspirators by the suction created when the air is expanded through the aspirator. Hence, the aspirator mechanism permits accurate control of the volume of air and products of combustion admixed therewith fed to each regenerator.

For operating the battery with an extraneously derived gas, such as producer gas, as the fuel burned in the flues, sections 1 and 3 of the several regenerators 28, 29 during their inflow period are connected to the producer gas main 51 through the valve-controlled manifold 45 so that the producer gas may be directed into sections 1 and 3 of the regenerators 29. The supply of coke oven gas to the channels 33, 33', 34, and 34' is, of course, shut off. A supply of producer gas

is permitted to flow into the inflow regenerator sections 1 and 3 of regenerators 29, and passing through these regenerators is preheated before delivery into the inflow groups of flues 1 and 3. Preheated air is delivered to the inflow groups 5 1 and 3 through the inflow regenerators 28, which may be supplied with air by the mains 91 and 92 or through valves (not shown) associated with each air regenerator and arranged to place the regenerator into communication with the atmosphere for inflow of atmospheric air thereinto. During the inflow of producer gas from regenerator sections 1 and 3 of regenerators 29, and air through the corresponding sections of regenerators 28, waste gas from the outflow operating flues 2 and 4 flow through the outflow regenerator sections 2 and 4 into the chimney flue on the coke side of the oven battery. On reversal of the flow, the inflow operating regenerators become outflow operating regenerators, 20 and concurrently, the outflow operating regenerators become inflow operating regenerators.

In operating the battery with coke oven gas, the supply of producer gas to the regenerator sections 1 to 3 of regenerator 29 is cut off and air is permitted to flow into all the inflow regenerator sections. Coke oven gas is simultaneously fed from the main 62, 64 to channels 33, 34' which feed the inflow flues. During one cycle of operation, air is fed from the air main 91 through 30 the aspirators in the channels 43, 55, 57 and 52 of each pair of regenerators, the air admixed with products of combustion from the chimney flue 41 introduced into the regenerator sections 1 and 3 and the mixture of air and products of 35 combustion supplied to groups 1 and 3 of the flues to which coke oven gas is fed, the products of combustion passing through regenerator sections 2 and 4 into the chimney flue 42. Upon reversal, air is fed from air main 92 through the aspirators 40 into the channels communicating with regenerator sections 2 and 4, the air admixed with products of combustion from the chimney flue 42 flowing through the regenerator sections 2 and 4 into groups 2 and 4 of the flues into which 45 coke oven gas is simultaneously supplied from the coke oven gas main, the products of combustion passing through groups 1 and 3 of the flues into regenerator sections 1 and 3 out into the chimney flue 41.

By the term "air" as used in the claims herein, it is intended to include all oxygen-containing gas employed to support combustion of fuel gas.

The invention as hereinabove described is embodied in a particular form of construction but it may be variously embodied within the scope of the following claims.

I claim:

1. In a regenerative coke oven battery comprising heating walls and coking chambers arranged side by side in alternate relation, each of said heating walls comprising combustion flues, crosswise extending regenerators disposed beneath the coking chambers communicating with the combustion flues and arranged in two groups, 60 one group operating for inflow while the other group simultaneously operates for outflow, a chimney flue with which the outflow group of regenerators communicates, an air main for containing air under pressure, passages connecting the inflow group of regenerators with said chimney flue, and an aspirator individual to each regenerator of the inflow group of regenerators, said aspirators communicating with said air main and said passages and arranged to aspirate prod- 65

ucts of combustion from the passages into the inflow group of regenerators.

2. In a regenerative coke oven battery comprising heating walls and coking chambers arranged side by side in alternate relation, each of said heating walls comprising combustion flues, crosswise extending regenerators disposed beneath the coking chambers communicating with the combustion flues and arranged in two groups, one group operating for inflow while the other group simultaneously operates for outflow, a chimney flue with which the outflow group of regenerators communicates, an air main for containing air under pressure, passages connecting the inflow group of regenerators with said chimney flue, an aspirator, individual to each regenerator of the inflow group of regenerators, communicating with said air main, a valve individual to each of the regenerators of the inflow group of regenerators for controlling flow of air from the main to the regenerator communicating therewith, and a valve in each passageway for controlling the amount of products of combustion aspirated into each inflow regenerator by the expansion of the air introduced into the inflow regenerator through the said aspirator.

3. In a regenerative coke oven battery comprising heating walls comprising combustion flues and defining coking chambers, the combustion flues being arranged in groups, adjacent groups of flues being communicably connected adjacent their top ends and arranged for simultaneous flow of gases therethrough in opposite directions, a regenerator communicably connected with each group of flues, a chimney flue at each side of the coke oven battery, means including passageways connecting one of said chimney flues with one group of regenerators operating for inflow, means including passageways connecting the other of said chimney flues with remaining regenerators operating for outflow, an air main communicably connected with the inflow group of regenerators, means including an aspirator individual to each of said inflow regenerators for introducing air from said main to said inflow regenerators, said aspirators being located in the passageways connecting the chimney flue with the inflow group of regenerators, valve means for controlling flow of air through said aspirators and valve means located in each of the passageways between the aspirators and the chimney flue for controlling the amount of products of combustion introduced by said aspirators from the chimney flue into the inflow regenerators.

4. A coke oven battery comprising horizontally elongated coking chambers and heating walls therefor, arranged side by side in a row in alternate relation, each of said heating walls comprising a plurality of equal groups of vertical combustion flues, the individual flues of each group being concurrently operable for flow in one direction while the flues of an adjacent group are operable for flow in the opposite direction, the groups of flues arranged for simultaneous flow in one direction alternating with the groups of flues for simultaneous flow in the opposite direction, each group of flues arranged for flow in one direction being connected with a contiguous group of flues arranged for simultaneous flow in the opposite direction, a regenerator system beneath said coking chambers comprising regenerators communicably connected with said flues and arranged in rows, each row extending crosswise of the battery, there being one regenerator in each row for each group of flues, a chimney flue at each side of the

battery, a pair of passages leading from the chimney flue at one side of the battery to alternate regenerators of each row beginning with the regenerator immediately adjacent to said chimney flue at the said one side of the battery, each of said passages being individual to a regenerator, located in the base thereof, communicably connected therewith and terminating at the end walls of the regenerators remote from the said chimney flue at the said one side of the battery, and a pair of passages communicably connecting the remaining regenerators of each row to the chimney flue at the other side of the battery, each of said passages being individual to a regenerator, located in the base thereof and leading from the end wall of the regenerator remote from the said chimney flue at the said other side of the battery to said chimney flue, each passage at each side of the battery leading to a manifold which communicates with a chimney flue at the side of the battery at which the manifold is disposed, an aspirator in each manifold at each side of the battery, an air main at each side of the battery communicably connected with the aspirators at each side of the battery, the discharge outlet of each aspirator being disposed in the passageway connecting the manifold with the chimney flue, and a valve individual to each manifold for controlling flow of air from the air main.

5. A coke oven battery comprising coking chambers and heating walls therefor arranged side by side in a row in alternate relation, each of said heating walls comprising vertical combustion flues disposed in two exterior and two interior groups of consecutively operable flues, the individual flues of each group being concurrently operable for flow in the same direction, alternating groups of flues being simultaneously operable for flow in the same direction, and the contiguous groups of flues being simultaneously operable for flow in opposite directions, each group of flues being connected with a contiguous group of outflow flues and a regenerator system beneath said coking chambers comprising regenerators arranged in rows of four, each row extending crosswise of the battery, each regenerator being individual to and communicably connected with two groups of flues, one on each side of the coking chamber thereabove, a pair of passages leading from the chimney flue at one side of the battery to alternate regenerators of each row beginning with the regenerator immediately adjacent to said chimney flue at the said one side of the battery, each of said passages being individual to a regenerator, located in the base thereof, communicably connected therewith and terminating at the end walls of the regenerators remote from the said chimney flue at the said one side of the battery, and a pair of passages communicably connecting the remaining regenerators of each row to the chimney flue at the other side of the battery, each of said passages being individual to a regenerator, located in the base thereof and leading from the end wall of the regenerator remote from the said chimney flue at the said other side of the battery to said chimney flue, each passage at each side of the battery leading to a manifold which communicates with a chimney flue at the side of the battery at which the manifold is disposed, an aspirator in each manifold at each side of the battery, an air main at each side of the battery communicably connected with the aspirators at each side of the battery, the discharge outlet of each aspirator being disposed in the passageway connecting the manifold with the chimney flue, a valve individual to

each manifold for controlling flow of air from the air main, and a second valve in each passageway connecting a chimney flue with a regenerator for controlling flow from the chimney flue to the 5 communicating regenerator.

6. In a coke oven battery involving heating walls and coking chambers, each of the heating walls comprising combustion flues arranged in two groups, one operating for inflow and the other 10 operating for outflow, means for feeding air to the inflow flues, means for controlling the volume of air fed to the inflow flues of each heating wall independently of the control of air fed to the inflow

flues of the other heating walls, means for mixing a neutral gaseous diluent with the air supplied to the inflow flues of each heating wall, and means for controlling the volume of neutral gaseous diluent supplied to the inflow flues of each heating wall independently of the feed of neutral gaseous diluent to the inflow flues of other heating walls, whereby the ratio of air to neutral gaseous diluent fed to one heating wall may be controlled independently of the ratio of air to 10 neutral gaseous diluent fed to the other heating walls.

CHARLES V. McINTIRE.
